UNITED STATES PATENT OFFICE.

FRANK M. EDGAR, OF DETROIT, MICHIGAN, ASSIGNOR TO TERNSTEDT MANUFACTURING COMPANY, OF DETROIT, MICHIGAN, A CORPORATION OF MICHIGAN.

PUNCH-PRESS GUARD.

Application filed November 30, 1923. Serial No. 677,650.

To all whom it may concern:

Be it known that I, FRANK M. EDGAR, a citizen of the United States, residing at Detroit, in the county of Wayne and State 5 of Michigan, have invented certain new and useful Improvements in Punch-Press Guards, of which the following is a specification.

This invention relates to punch press 10 guards. It is not broadly new to provide a punch press with a guard so coupled up with the clutch release that the clutch or trip cannot be disengaged until the hand guard is completely down. Numerous 15 patents in the prior art show devices for this purpose. Nor is it broadly new to couple up with the punch press guards a positive stop which is not removed from the path of the clutch release until the guard is way down.

20 My improvement belongs to punch press guards of the latter type, but has an improved arrangement of structure to make the operation of the parts more reliable and easier, and the counterbalancing device is 25 coupled up directly to the clutch release stop so that the stop will be reliably returned into the path of the clutch release or tripping device when the guard is drawn upwardly. So far as I am aware all punch 30 press guards which are coupled up with the clutch release are calculated to severely pinch the hand if the operator's hand is caught under the guard. I have an arrangement whereby a yieldable connection is afforded in the draft line between the pedal and the guard, whereby the hand receives only the impact of the guard and any foot 35 pressure is absorbed in the spring so that pressure of the foot as long as continued 40 on the pedal does not serve to painfully pinch the hand.

In the drawings:

Fig. 1 is an elevational view of a punch press showing the guard assembled thereon.

45 Fig. 2 is a section on the line 2—2 of Fig. 1.

Fig. 3 is a section on the line 3—3 of Fig. 2.

50 Fig. 4 is a detail in perspective of the grooved block.

Fig. 5 is a section on the line 5—5 of Fig. 1 showing the adjustments for correctly positioning the guard with respect to the dies.

Fig. 6 is a section on the line 6—6 of 55 Fig. 1 showing the yieldable connection between the guard and the draft member.

Fig. 7 is a section on the line 7—7 of Fig. 1.

Fig. 8 is a detail in perspective of one 60 corner of the guard plate.

A punch press *a* rotatably supports a shaft *b* to which is secured the pulley *c* and the shouldered trip collar *d* which is attached to any suitable clutch mechanism 65 (not shown). The male die *e* is carried by a suitable plunger which is operated in a familiar way. The female die *f* is carried by the base plate *g* supported on the machine.

Secured on the side of the machine and spaced therefrom is a plate *h*, which is provided with a slot *i* in which a grooved block *j* is slidably engaged. This grooved block is tapped as at *k* and the rod *m* is 70 screwed into the stud *n* which is in turn screwed into the tapped hole *k* to positively connect the grooved block with the stop *o*. The stop *o* is adapted to engage the trip collar *d* to prevent the machine from being 75 operated to force the dies *e* and *f* together. (See Fig. 2.) A pin *p* is carried by the grooved slide and a draft bar *q* provided with an elongated slot *r* is secured to the block by means of the said stud *p*. The 80 extreme lower end of the bar *q* is secured to a rod *s* which is in turn secured to the foot pedal *t*. Obviously as the foot pedal is depressed it will pull the bar *q* downwardly tending to disengage the stop *o* and 85 shouldered trip collar *d*.

However, additional mechanism is provided which will prevent the stop from becoming disengaged from the shouldered trip collar until the operator withdraws his 90 hands from between the dies. The guard arm *u* is pivoted to the machine as at *v* (see also Figs. 6 and 7) and adjustably supports on the free end thereof a bracket *w* which in turn adjustably supports the 95 guard plate *x*. At an intermediate portion of the said guard arm is secured a fixture *y* which is cut away as at *z* (Fig. 7) to provide an opening through which the draft bar *q* may be slidably supported. The 100 guard arm *u* carries a pin *1* which is adapted to engage in the elongated slot *2* in the draft bar *q*. A bracket *3* is secured to the 105

bar *q* and a pin *4* connects the bracket *3* and pin *1*. A coiled compression spring *5* is interposed between the bracket *3* and the pin *1* and normally forces the pin downwardly to the full extent of the slot *2*. This spring is of such a strength that as the foot lever is depressed carrying with it the draft member *q*, it will not be compressed to any appreciable extent but will force the 10 guard arm *u* downwardly and as the foot pedal is depressed to the full extent of its movement, the guard arm plate *a* will assume a position as shown in the full lines of Fig. 1. The dotted line position of the 15 guard in Fig. 1 shows the inoperative position of the same, i. e., when the foot pedal is raised and the stop *o* is in engagement with the shouldered trip collar *d*.

Pivoted to the plate *h* as at *6* is a segmental stop *7* which is provided with an arm extending to the rear of the machine to which is secured a counterweight *8*. In Figs. 1 to 4 inclusive, one will notice that the segmental stop *7* when in an interfering position 25 is positioned directly below the grooved block thereby preventing the same from being pulled downwardly when the draft member is pulled down. As the draft member is pulled down the pin *p* will travel in the slot 30 *r* and allow a relative movement between the draft member and the block *j* carried by the tripping mechanism. The segmental stop, however, is also provided with an arm 35 *9* the free end of which is connected to the guard arm *u* by means of a link *10*. As the foot lever is depressed the guard arm will be drawn downwardly from the dotted line position to the full line position and through the connecting link *10* and actuate 40 the segmental stop *7* so as to rotate the same in a counter-clockwise direction thus moving the cam from an interfering position to a non-interfering position with respect to the grooved block *j*. The guard 45 plate is so adjusted that when the plate reaches a position shown in full lines in Fig. 1 the segmental stop will just release the block *j*, to allow the same to be pulled downwardly by the draft member through 50 the pin and slot connection. This will disengage the stop *o* from the shoulder trip *d* and allow the operating mechanism to reciprocate the plunger so as to bring the dies together. Another function of the spring 55 *5* is to allow the draft member *q* to be pulled downwardly after the guard is stopped. When the guard reaches the full line position, the segmental stop *7* releases the grooved block and the spring *5* is compressed on further movement of the foot 60 pedal to allow for the relative movement between the draft member and the guard in tripping the machine.

The grooved block *j* is cut away as at 65 11 to allow only a limited movement of

the block in releasing the stop *o*. The shoulder *12* is adapted to strike the segmental stop to stop further downward movement of the block and hence prevents any further movement of the stop *o* than is necessary to release the collar *d*. 70

What I claim is:

1. In a guard for a punch press or similar machine, the combination of operating mechanism, means for controlling the operating mechanism and provided with a tripping mechanism having a slidable member, a draft member having a lost motion connection with the tripping mechanism, a stop in the form of a sector which is swung 75 in the path of said slidable member which is part of said tripping mechanism for preventing the same from being actuated, and a guard yieldably connected to said draft member and positively connected to the 80 stop, whereby the operating mechanism is held in an inoperative position until the guard is lowered to a position in front of the work thereby retracting the stop to allow the draft member to actuate the tripping mechanism and preventing the operator from inserting his hands while the machine is in operation.

2. In a guard for punch press or similar machine, the combination of mechanism for operating the machine, means for tripping the operating mechanism, a draft member slidably supported on the machine and connected with said tripping means, a guard pivotally supported on the machine, a stop 95 arranged to be engageable with said tripping means, a bracket carried by the draft member, said draft member provided with a slot, a pin carried by the guard projecting through said slot, and a spring interposed 100 between said bracket and pin to provide a yieldable connection between the draft member and guard, the said slot limiting the relative movement between the two.

3. In a guard for punch press or similar machine, the combination of mechanism for operating the machine, means for tripping the operating mechanism and including a block slidably supported on the machine, said block provided with a pin, a draft member provided with an elongated slot which engages with the pin for the purpose of providing a lost motion connection between the draft member and the block, a stop normally engaged under the block to prevent the tripping means from releasing the operating mechanism, and a guard connected with said stop and yieldably connected with the draft member, whereby as the draft member is pulled downwardly the guard is lowered to a protecting position in front of the work thereby actuating the stop to remove the same from beneath the block to allow the tripping of the operating mechanism for the purpose of setting the ma- 110 115 120 125 130

chine in operation when the guard is lowered.

4. In a guard for a punch press or similar machine, the combination of an operating mechanism, means for tripping the operating mechanism, a draft member having a lost motion connection with the tripping means, a stop normally engaged with the tripping means to render it inoperative and provided with a forwardly extending arm and a rearwardly extending arm having a counterbalancing member secured thereto for normally holding the stop in such position, a guard pivoted to the machine and connected to said draft member, and a link

connection between the guard and the forwardly extending arm carried by the stop whereby a pull on said draft member will lower the guard into a protecting position in front of the work and actuate the stop to 20 disengage the same from the tripping means, for the purpose of tripping the operating mechanism and setting the machine into operation, the said counterbalancing member tending to return the guard and 25 stop to their normal position when the pull on said draft member is released.

In testimony whereof I affix my signature.

FRANK M. EDGAR.
